United States Patent

Des. 237,787

Patented Nov. 25, 1975

237,787

TRASH CAN CART

Victor L. Weyrich, Jr., Spearfish, S. Dak., assignor to
Fibco Enterprises, Inc., Spearfish, S. Dak.

Filed May 31, 1974, Ser. No. 475,159

Term of patent 14 years

Int. Cl. D12—02

U.S. Cl. D12—34

FIG. 1 is a perspective view of a trash can cart of my new design;

FIG. 2 is a top plan view thereof;

FIG. 3 is an end elevational view thereof;

FIG. 4 is an end elevational view thereof opposite to that shown in FIG. 3;

FIG. 5 is a bottom plan view thereof; and

FIG. 6 is a side elevational view thereof; the opposite side being a mirror image of the side shown herein.

I claim:

The ornamental design for a trash can cart, as shown and described.
